UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

FEEDING MECHANISM FOR SEWING-MACHINES.

1,368,245.

Specification of Letters Patent. Patented Feb. 15, 1921.

Application filed November 21, 1916. Serial No. 132,521.

To all whom it may concern:

Be it known that I, ALBERT H. DE VOE, a citizen of the United States, residing at Westfield, in the county of Union and State of New Jersey, have invented certain new and useful Improvements in Feeding Mechanisms for Sewing-Machines, of which the following is a specification, reference being had therein to the accompanying drawings.

This invention relates to sewing machines and particularly to feeding mechanisms therefor in which differentially actuated members are moved to gather or full fabric in advance of the presser-foot in order that it may be subsequently sewed in either a ruffled or a substantially normal condition free from distortion according to the character of the work.

It has for its object to provide an improved high speed differentially movable feeding mechanism which is simple in construction, compact, readily adjustable and quick acting.

Further objects of the invention are to provide mechanism for imparting four-motions to an upper feeding member from a single driving shaft and through connections that permit the lengths of the feeding and lifting strokes thereof to be varied, and to provide means for controlling the force with which the upper feeding member is impinged against the fabric.

And another object of my invention is to provide in a differential feeding mechanism automatic means for uniformly fulling material regardless of its thickness so that several pieces of material of the same length but of different thickness may be separately stitched to a body fabric and, finished, will be of the same length.

These and other objects are realized in my construction in which a needle driving rock shaft is provided with a crank-disk driving a sector-plate which is spring-pressed to frictionally engage a feed-blade-carrying-arm against the disk thus affording a frictional driving connection for imparting lifting movements to the blade, the feeding movements of the blade being derived from a pivoted hanger pivotally supporting the arm carrying the blade, through a crank-pin block adjustably mounted on the crank-disk. Stop pins are provided for limiting the lifting movements of the blade.

The pivoted supporting lever for the hanger

is slidingly connected with a pin carried by the presser-bar with which pin the cam portion of an ordinary presser-foot lifting lever is adapted to engage to effect a simultaneous elevation of the presser-foot and blade.

My invention also consists in certain details of construction which will appear in the description of the embodiment of my invention shown in the drawings in which Figure 1 is an end elevation of the head of the machine with the face-plate removed; Fig. 2 is a sectional side elevation; Fig. 3 is a perspective view from the rear of the machine; Fig. 4 is a perspective view of the face-plate and parts carried thereby; and 70 perspective views, Fig. 5 of the crank-disk, Fig. 6 of the blade and arm, Fig. 7 of the hanger, and Fig. 8 of the presser-foot, visualize the details of construction.

In the illustrated embodiment of my invention needles 1, of any suitable form of stitching mechanism, are carried by a needle-bar 2 driven through a link 3 and crank-arm 4 fast to a rock-shaft 5. A crank-disk 5', driven in any suitable manner from the rock-shaft but preferably, as shown, connected for movement with the rock-shaft through a bent-arm 6 secured by screws 7 in a seat 8 in a block or enlargement 9 integral or fastened to the crank-arm 4, is provided with connections for imparting both feeding and lifting movements to an upper feeding member or blade indicated at 50.

The conversion of the oscillatory motion of the crank-disk into feeding movements of the blade is effected through a hanger pivoted intermediate its ends and oscillated by a crank construction carried by the disk and embraced by the upper end of the hanger, a blade being pivotally supported at the lower end of the hanger for movement independently thereof for a purpose to be hereinafter described. Specifically the connections comprise a block 10 loosely mounted on a crank-pin 11 fixed by a lock-nut 12 on its threaded portion 13 to a slide 14 which is movable in a guideway 15 in the crank-disk 5' and through suitably disposed slots 16 and screw 17 radially shiftable to vary the length of the feeding movements of the blade. A hanger 18 pivoted for movement about an axis intermediate its ends is slotted at its upper end 19 to embrace the crank-pin-block 10 and at its lower end the hanger is provided with a slot 20 through which is passed

a clamp-screw 21 for adjustably securing to the hanger a bearing 22 affording a pivotal support for an upper feeding member or blade to be later described.

5 The conversion of the oscillations of the crank-disk into lifting movements of the blade is effected through an arm pivoted to the lower end of the hanger and fixedly connected with the blade which, as arranged, is 10 movable in an arc substantially transverse to the arc of movement of the lower end of the hanger, the arm being oscillated by the crank-disk through a frictional driving device. Specifically the connections comprise 15 a sector-plate 30, Figs. 2 and 4, oscillated about the same axis as the rock-shaft 5 on a pin 31 journaled in the boss 32 on the face-plate 33 which is removably attached by screws 34 to the head 35 of the machine, 20 the pin 31 being reduced at 37 to afford a shoulder 38 against which a coiled spring 39 surrounding the reduced extension 37 is adapted to bear to thrust the sector-plate toward the crank-disk, the other end of the 25 coiled spring bearing against an adjustable abutment in the form of a thumb-screw 40 threaded into the boss 32 and drilled at 41 to receive the free end of the reduced extension 37, a knurled nut 42 affording means 30 for locking the abutment in place. The crank-disk 5' is provided with a wear-plate 43 and is drilled at 44 eccentrically to receive a pin 45 carried by the sector-plate 30 the same distance from the axis of oscillation, 35 thus establishing a driving connection between the plate and disk. The upper feeding member 50, herein shown, has a relatively stiff blade but obviously other forms of fabric-engaging elements could be used, is provided with an ear 51 adjustably secured in any suitable manner as at 52 to the bent-arm 53 of an attachment bar 54 provided with a laterally arranged pin 55 fixed by a set-screw 56 within a bearing bushing 57 which 40 is journaled in the bearing 22 of the hanger and affords a pivotal support for an arm 60 extending upwardly between the crank-disk and sector-plate frictionally engaged with the upper end thereof and imparting lifting 45 movements to the blade therethrough. A collar 61 is secured by a set-screw 62 on the bearing bush 57 to prevent endwise movement thereof in the bearing 22. A short pin 63, also carried by the attachment bar 54, engages in a slot 64 in a lever-arm 65 fast on the bearing bush and insures against 50 rotation of the attachment bar 54 on the pin 55 secured in the bearing bushing as well as takes the strain off the set-screw 56. Thus 55 the arm 60, the bearing bushing 57 and the attachment bar 54 carrying the blade are fixedly connected together and establish an operative connection between the rock-shaft and the blade frictionally driven through 60 the spring-pressed plates.

For limiting the amplitude of the lifting movements of the blade, stops are provided consisting of pins 70 carried by the slide-blocks 71 fitted in a guideway 72 inside of the removable face-plate 33 and adjustable 70 through the agency of slots 73 in the face-plate receiving screws 74 tapped into the slide-blocks. These stops are arranged transverse to the plane of oscillation of the arm 60 driven by the friction plates and in 75 the path of movement of the arm so that the arm may be restrained from moving with the friction plates before they have completed their oscillatory movements and thus permitting lost-motion between the arm 80 and the friction plates. In this way there is provided means for limiting the amplitude of the lifting movements of the blade and thus, within certain limits the approach of the blade to the plane of the feed-dog 85 75, with which the machine is provided, may be predetermined.

As it is desirable to raise the gathering, ruffling or fulling blade 50 with the presser-foot 76 the pivot intermediate the ends of 90 the hanger is suitably connected for movement with the presser-foot. The hanger is provided intermediate its ends with the pivot pin 80 confined by a collar 81 against endwise movement within a bearing 82 carried by a lifting and supporting lever 83 pivoted at 84 to a fixed part of the head and provided with an inclined slot 85 adapted to embrace a friction roller 86 on a pin 87 fixed in a yoke 88 having spaced bosses 89 100 fitted to the presser-bar 90 carrying the presser-foot 76 above and below a block 91 fastened to the presser-bar by a set-screw 92. A lifting lever 93 having a cam-face 94 adapted to bear against the roller serves 105 to permit simultaneous elevation of the presser-foot and blade through the supporting and lifting lever connected by the pivot-pin 80 with the hanger 18 in the lower end of which the blade 50 is pivotally supported. 110 In addition to the lifting lever any suitable treadle operated lifting means may be connected with the yoke 88 but being old and well-known it is not deemed necessary to 115 illustrate the same.

It is to be noted that arm 60 and consequently blade 50 are vibrated instantly upon the reversal of the rock-shaft, thereby effecting a rapid grip and release of the fabric immediately upon commencing the 120 forward and backward feeding movements of the blade. This facilitates a fulling action in advance of the feeding action of the main feed-dog upon the work and enables the blade to be withdrawn from the 125 work before the feed-dog has been dropped below the elevation of the throat-plate at the end of its feed stroke.

Adaptability to different thicknesses of goods flows from pivotally supporting the 130

hanger carrying the blade to the lifting and supporting lever which is shifted up and down according to the thickness of the goods through connections with the presser-
5 foot.

As the presser-foot rises and falls with variations in the thickness of fabric passing thereunder, the pivot-pin 80 and the hanger 18 are shifted. Obviously this results in
10 increasing or decreasing the vibration of the hanger by the crank-pin-block, the throw of which is constant for any given adjustment, and consequently with thicker goods the blade 50 supported in the lower
15 end of the hanger is given a greater sweep than with thin goods and vice versa. This action is automatic and is to be distinguished from the adjustment of the blade up and down vertically to maintain it approxi-
20 mately in a plane with the lower surface of the presser-foot. Likewise varying the distance between the pivot-pin 55 and the stops 71 produces variations in the lifting move-
25 ments of the blade according to the thickness of fabric.

Materials differ in character some being softer than others. The depth with which the blade sinks into the goods may be suited to the character of the work by adjusting
30 one of the stops 70, in this case the forward stop. The force with which the blade im-
pings against the material may be made light enough for the thinnest of fabrics and heavy enough for the thickest knit goods
35 which have any tendency to stretch by a simple rapid manipulation of the thumb-
screw 40 to vary the tension with which the coiled spring 39 thrusts the sector-plate 30 toward the crank-disk 5' to frictionally en-
40 gage and drive the arm 60 connected with the blade.

While I have shown and described the invention as embodied in a fulling feed mechanism, it is to be understood that I do
45 not wish to be limited thereto because by obvious changes in proportion the blade may be given feeding movements, or lifting movements, or both, of amplitude suffi-
ciently great to gather or ruffle material.

50 In certain broad aspects my invention embraces a construction in which the friction-driving connection is replaced by any other suitable mechanism for imparting lifting movements to the dog, it being ob-
55 vious for example that a link between the crank-disk 5' and arm 60 could be used in lieu of the spring-pressed sector-plate. And also it is to be understood that my invention broadly in some aspects is capable of appli-
60 cation to an under as well as an upper feed-
ing mechanism.

Having thus set forth the nature of the invention, what I claim herein is: —

65 1. In a sewing machine, in combination with a stitching mechanism, a fulling feed

having a fabric-engaging element arranged for operation on fabric in advance of the stitching mechanism, and means for imparting four motions to said fabric-engaging element including a friction-driving con-
70 nection.

2. In a sewing machine, in combination with a stitching mechanism, a fulling feed having a fabric-engaging element arranged for operation on fabric in advance of the stitching mechanism, means for imparting feeding movements to said fabric-engaging element, and means for imparting thereto lifting movements including a friction-
75 driving connection. 80

3. In a sewing machine, the combination with stitching mechanism, a feed-dog, a presser-foot, a fulling feed having a fabric-
85 engaging element arranged for operation on fabric in advance of the presser-foot, a rock-
shaft, and means driven by said rock-shaft for imparting feeding and lifting move-
ments to said fabric-engaging element.

4. In a sewing machine, the combination with a stitching mechanism, a fulling feed 90 having a blade arranged for operation on fabric in advance of the stitching mechanism, an arm connected with said blade, and means for imparting four motions to said blade including a friction-driving connec-
95 tion comprising plates yieldingly engaged with opposite sides of said arm. 95

5. In a sewing machine, in combination with a stitching mechanism, a feed-dog, a presser-foot, a fabric-engaging element ar-
100 ranged for operation on fabric in advance of the presser-foot, means for imparting four motions to said fabric-engaging element in-
cluding a friction-driving connection and means for varying the amount of friction 105 thereof.

6. In a sewing machine, in combination with stitching mechanism, a feed-dog, a presser-foot, a blade arranged for operation on fabric in advance of the presser-foot, an 110 arm connected with said blade, and means for imparting four motions to said blade in-
cluding a friction-driving connection com-
prising, a crank-disk and a sector-plate
yieldingly thrust toward said crank-disk,
115 said arm being arranged between said crank-
disk and said sector-plate.

7. In a sewing machine, in combination with stitching mechanism, a feed-dog, a presser-foot, a rock-shaft, a blade arranged 120 for operation on fabric in advance of the presser-foot, an arm connected with said blade, and means for imparting four motions to said blade including a friction-driving connection comprising, a crank-disk and a 125 sector-plate yieldingly thrust toward said crank-disk, said arm being arranged be-
tween said crank-disk and said sector-plate,
said sector-plate and crank-disk having a
common axis of oscillation. 130

8. In a sewing machine, in combination with stitching mechanism, a feed-dog and a presser-foot, an upper feeding member arranged for operation on fabric in advance 5 of the presser-foot, an arm connected with said upper feeding member, means for imparting four motions to said upper feeding member including a friction-driving connection comprising, plates engaged with opposite 10 site sides of said arm and means for varying the amount of pressure with which said plates engage the arm.

9. In a sewing machine, in combination with stitching mechanism, a feed-dog, a presser-foot, a hanger pivotally supported intermediate its ends, a blade pivotally mounted on the lower end of said hanger, an arm connected with said blade, means frictionally engaging said arm to impart lifting 15 movements to said blade, and means for imparting feeding movements to said blade connected with the upper end of said hanger.

10. In a sewing machine, in combination, a presser-foot, a hanger pivoted for movement 25 about an axis intermediate its ends, a blade pivoted for movement about an axis passing through the lower end of said hanger, an arm connected with said blade, a rock-shaft, a crank-disk carried thereby, and operative connections between said crank-disk 30 and both the arm and the upper end of said hanger for imparting four motions to said blade.

11. In a sewing machine, a presser-foot, a hanger pivoted for movement about an axis intermediate its ends, a blade pivoted for movement about an axis passing through the lower end of said hanger, an arm connected 35 with said blade, a rock-shaft, a crank-disk carried thereby, and operative connections between said crank-disk and both the arm and the upper end of said hanger for imparting four motions to said blade including means for frictionally driving said arm 40 from said crank-disk.

12. In a sewing machine, a presser-foot, a hanger pivoted for movement about an axis intermediate its ends, a blade pivoted for movement about an axis passing through 50 the lower end of said hanger, an arm connected with said blade, a rock-shaft, a crank-disk carried thereby, and operative connections between said crank-disk and both the arm and the upper end of said hanger for imparting four motions to said blade.

13. In a sewing machine, in combination with stitching mechanism, a presser-foot and a coöperating feed-dog, an upper feeding member arranged to engage the fabric in advance 60 of said coöperating foot and dog and differentially movable with relation to said dog, means for imparting feeding movements to said upper feeding member, means for imparting lifting movements thereto, and one or more stops for controlling the 65

amplitude of the lifting movements of said upper feeding member.

14. In a sewing machine, in combination with feeding mechanism, a hanger pivotally supported between its ends, a blade pivotally mounted on the lower end of said hanger, an arm fixedly connected with the said blade, means for imparting through said arm lifting movements to said blade, and means for imparting feeding movements to said blade 75 through the upper end of said hanger.

15. In a sewing machine, in combination with stitching mechanism, a feed-dog and a coöperating presser-foot, means for lifting said presser-foot, a lifting and supporting lever pivoted for movement about a fixed axis, a loose connection between said lever and said presser-foot for supporting the lever, a hanger pivotally supported on said lifting and supporting lever, an upper feeding member pivotally supported on the lower end of said hanger, an arm connected with the upper feeding member, and means operatively connected with said arm and said upper end of the hanger for imparting four 80 motions to said upper feeding member.

16. In a sewing machine, in combination, a presser-foot, an upper feeding member, means for imparting lifting movements thereto, a hanger pivotally supporting the feeding member and being in turn pivoted for movement about an axis intermediate its ends, a driving shaft, a crank-disk carried thereby and a crank-pin block adjustably supported on said crank-disk, said hanger 100 having its upper end slotted to embrace said crank-pin block whereby feeding movements may be given to the upper feeding member.

17. In a sewing machine, in combination, a presser-foot, a feed-dog, a driving shaft, a crank-disk operated thereby, a sector-plate driven by and pivoted coaxially with said crank-disk, an arm arranged between said crank-disk and said sector-plate, a spring urging said sector-plate toward said crank-disk, means for adjusting the tension of said spring, an upper feeding member connected with said arm and pivoted for movement therewith, and operative connections for imparting feeding movements to said upper 115 feeding member.

18. In a sewing machine, in combination, a presser-foot, a feed-dog, a feeding member, a pivoted hanger pivotally supporting said feeding member, a crank-disk, means 120 for oscillating said crank-disk, a crank-pin carried by the disk, operative connections between said crank-pin and the upper end of said hanger whereby the feeding member may be given feeding movements, a sector-plate driven by and pivoted coaxially with said crank-disk, an arm connected to said feeding member and arranged between the disk and sector-plate, and a spring urging said sector-plate toward the disk whereby 125

the feeding member may be given lifting movements.

19. In a sewing machine, in combination, a presser-foot, a feed-dog, a feeding member, a pivoted hanger pivotally supporting said feeding member, a crank-disk; means for oscillating said crank-disk, a crank-pin carried by the disk, operative connections between said crank-pin and the upper end of 5 said hanger whereby the feeding member may be given feeding movements, a sector-plate driven by and pivoted coaxially with said crank-disk, an arm connected to said feeding member and arranged between the 10 disk and sector-plate, a spring urging said sector-plate toward the disk whereby the feeding member may be given lifting movements, and one or more stops for limiting the vibration of said arm whereby the amplitude of the lifting movements may be 15 predetermined.

20. In a sewing machine, in combination with stitching mechanism, a presser-foot and a coöperating feed-dog, an upper feeding member arranged to engage fabric in advance of said coöperating foot and dog and differentially movable with relation to said dog, means for imparting feeding movements to said upper feeding member, means 25 for imparting lifting movements thereto, including a frictional driving connection and one or more stops for controlling the amplitude of the lifting movements of the upper feeding member.

35 21. In a sewing machine, in combination with stitching mechanism, a presser-foot and a coöperating feed-dog, an upper feeding member arranged to engage fabric in advance of said coöperating foot and dog and 40 differentially movable with relation to said dog, means for imparting feeding movements to said upper feeding member, means for imparting lifting movements thereto, including a driving connection permitting 45 lost-motion and means for determining the amount of lost-motion.

22. In a sewing machine, in combination with stitching mechanism, a presser-foot and a coöperating feed-dog, an upper feeding member arranged to engage the fabric in advance of said coöperating foot and dog and differentially movable with relation to said dog, means for imparting feeding movements to said upper feeding member, 50 means for imparting lifting movements thereto, including a frictional driving connection comprising spaced plates, an arm connected with said upper feeding member and arranged therebetween, and means 55 for pressing the plates and arm together, and stops for limiting the movement imparted to said arm through said plates.

60 23. In a sewing machine having stitch-forming mechanism including a needle, in combination, coöperating dog and presser

elements for advancing the work, an auxiliary feeding member movable differentially with relation to said dog and operating upon the work in advance of the needle, means for imparting lifting movements to said member, means for imparting feeding movements to said member, and automatic means for varying the length of feeding movements imparted to said member according to the thickness of material. 70

24. In a sewing machine having stitch-forming mechanism including a needle, in combination, coöperating dog and presser elements for advancing the work, an auxiliary feeding member movable differentially 80 with relation to said dog and operating upon the work in advance of the needle, means for imparting feeding movements to said member, means for imparting lifting movements to said member and connected with 85 the presser element so that the length of the lifting movements imparted to said member are automatically varied according to the thickness of the work.

25. In a sewing machine having stitch-forming mechanism including a needle, in combination, coöperating dog and presser elements for advancing the work, an auxiliary feeding member movable differentially 90 with relation to said dog and operating upon the work in advance of the needle, means for imparting feeding and lifting movements to said member, and automatic means for varying the amplitude of said feeding and lifting movements according to the 95 thickness of the work.

26. In a sewing machine having stitch-forming mechanism including a needle, in combination, coöperating dog and presser elements for advancing the work a stitch 105 length at a time, an upper feeding member movable differentially with relation to said dog and operating upon the work in advance of the needle, means for imparting lifting movements to said member, means for imparting feeding movements to said member, and automatic means for varying the length of feeding movements imparted to said member according to the thickness of material. 110

27. In a sewing machine having stitch-forming mechanism including a needle, in combination, coöperating dog and presser elements for advancing the work a stitch length at a time, an upper feeding member 115 movable differentially with relation to said dog and operating upon the work in advance of the needle, means for imparting feeding movements to said member, means for imparting lifting movements to said member and connected with the presser element so 120 that the length of the lifting movements imparted to said member are automatically varied according to the thickness of the work.

28. In a sewing machine having stitch- 130

- forming mechanism including a needle, in combination, coöperating dog and presser elements for advancing the work a stitch length at a time, an upper feeding member 5 movable differentially with relation to said dog and operating upon the work in advance of the needle, means for imparting feeding and lifting movements to said member, and automatic means for varying the 10 amplitude of said feeding and lifting movements according to the thickness of the work.
29. In a sewing machine having stitch-forming mechanism including a needle, in combination, a main feed-dog and a presser-foot 15 coöperating therewith to advance the work a stitch length at a time, an auxiliary feeding member movable differentially with relation to said dog and operating upon the work in advance of the needle, and means 20 connected with the presser-foot so as to be controlled by the thickness of the work for automatically varying the action of the auxiliary member as the thickness of the work varies.
- 25 30. A sewing machine, in combination with the stitch-forming mechanism, a feed having a fabric engaging element, and means for imparting feeding and lifting movements to said element including a friction 30 driving connection comprising a moving driving member and a driven member actuated thereby through frictional contact with the driving member and said frictional drive adapted to move the driven member 35 in a plurality of directions.
31. In a sewing machine, in combination with stitch-forming mechanism, a feed having a fabric engaging element, means for imparting feeding movements to said fabric 40 engaging element, and means for imparting thereto lifting movements including a friction driving connection comprising a moving driving member and a driven member actuated thereby through frictional contact 45 with the driving member and said frictional drive adapted to move the driven member in a plurality of directions.
32. In a sewing machine, the combination with stitch-forming mechanism, a feed-dog, 50 a presser-foot, an auxiliary feed having a fabric engaging element, a rock-shaft, and means driven by said rock-shaft for imparting feeding and lifting movements to said fabric-engaging element including a friction 55 driving connection.
33. In a sewing machine, the combination with stitch-forming mechanism, a feed-dog, a presser-foot, an auxiliary feed having a fabric engaging element for operating on 60 the work in advance of the stitching mechanism, a rock-shaft, and means driven by said rock-shaft for imparting feeding and lifting movements to said element including a friction-driving connection.
34. In a sewing machine, in combination 65 with stitch-forming mechanism, feeding and coöperating presser means for advancing the work, an auxiliary feed comprising an element adapted to engage the work in advance of the stitch-forming mechanism, 70 means for imparting feeding and lifting movements to said element including a friction drive and means for limiting one of said movements including an adjustable stop. 75
35. In a sewing machine, in combination with stitch-forming mechanism, feeding mechanism and a coöperating presser element, an auxiliary feeding means including an element operating on the work in advance of the stitch-forming mechanism, means for imparting feeding and lifting movements to said elements including a friction driving connection permitting lost motion and means for determining the 80 amount of lost motion.
36. In a sewing machine having stitch-forming mechanism including a needle, in combination, coöperating dog and presser-elements for advancing the work, an auxiliary feeding member movable differentially with relation to said dog and operating upon the work in advance of the needle, means for imparting feeding movements to 90 said member and means whereby the feeding movements are automatically varied with variations in the thickness of material 95 being sewed.
37. In a sewing machine having stitch-forming mechanism including a needle, in combination, a main feed-dog and a presser-foot coöperating therewith to advance the work a stitch length at a time, an auxiliary feeding member movable differentially with relation to said dog and operating upon the work in advance of the needle, and means 100 controlled by the presser-foot for causing variations in movements of the auxiliary member with variations in the thickness of the work. 105
38. In a sewing machine, in combination with the stitching mechanism, a feeding element, means for imparting movements to said element, including a moving driving member and a driven member having frictional driving engagement with the first member, said driving member adapted to move said driven member in at least two directions. 115
39. In a sewing machine, in combination 120 with the stitching mechanism, a feeding element, an oscillating driving member, an adjustable element mounted thereon, means for transmitting motion from the adjustable element to the feeding element, a driven 125 member having frictional driving engagement with the driving member, adjustable means for limiting the movements of the

driven member and means for transmitting motion from the driven member to the feeding element.

40. In a sewing machine, in combination with stitch-forming mechanism, feeding mechanism and a coöperating presser element, an auxiliary feeding means including an element operating on the top of the work in advance of the stitch-forming mechanism,

means for imparting feeding and lifting movements to said element including a driving connection permitting lost motion and means for determining the amount of lost motion.

In testimony whereof, I have signed my name to this specification.

ALBERT H. DE VOE.
